UNITED STATES PATENT OFFICE.

DILLWYN M. BELL, OF CHICAGO, ILLINOIS, AND JOHN C. FOGARTY, OF GREEN BAY, WISCONSIN, ASSIGNORS TO NORTHERN PAPER MILLS, OF GREEN BAY, WISCONSIN, A CORPORATION OF WISCONSIN.

PAPER-SERVING MACHINE.

1,116,787.

Specification of Letters Patent.

Patented Nov. 10, 1914.

Application filed March 27, 1913. Serial No. 757,091.

To all whom it may concern:

Be it known that we, DILLWYN M. BELL and JOHN C. FOGARTY, citizens of the United States, residing at Chicago, in the county of 5 Cook and State of Illinois, and Green Bay, in the county of Brown and State of Wisconsin, respectively, have invented a certain new and useful Improvement in Paper-Serving Machines, of which the following 10 is a full, clear, concise, and exact description.

Our invention relates to paper serving machines of the type which holds a bunch of sheets of paper and delivers the sheets, one at a time, from an inclosing casing.

15 It constitutes an improvement upon United States Patent No. 604,113, granted May 17th, 1898, upon an application of Charles Fisher.

The objects of our invention are; to provide a paper serving machine of the type mentioned, in which the delivery of the successive sheets is more certain and assured than heretofore; in which the case is so closed that it is proof against being tampered with from the outside; which may be readily refilled when the paper supply is exhausted; and which lends itself to economical manufacture.

In the accompanying drawings we have 30 illustrated the preferred embodiment of the invention.

Figure 1 is an elevation partly in section taken on the line 1—1 of Fig. 2; Fig. 2 is a sectional elevation on the line 35 2—2 of Fig. 1; and Fig. 3 is an elevation of a detail.

The casing comprises, generally speaking, two hinged portions, the rear portion 1 being adapted to be secured to a suitable support 40 and constituting the body of the casing, and the front portion 2 constituting the cover therefor, said front and rear portions being hinged to each other at the point 3, and normally locked in closed position by a suitable 45 lock 4, which may be of any standard construction. Within the body of the casing a friction roller 5 is rotatably mounted, said roller in its preferred form consisting of a wooden cylinder having preferably a plurality 50 of friction bands 6 of rubber fabric, or other suitable material, encircling the same. Said roller is fixed to a suitable spindle 7, the latter having at one end a knurled knob or handle 8, whereby the roller 55 may be readily rotated directly by hand if

necessary, and having at the other end a ratchet 9 adapted to coöperate with a suitable pawl 10 to prevent backward rotation of the roller. The pawl 10 is pivotally supported on the casing 1 and is provided with 60 a projecting lug 11 which is received within a slot 12 in the said casing, said lug and slot limiting the movement of said ratchet.

The spindle 7 is received at opposite ends within a pair of diagonally extending slots 65 13 arranged in the side walls of the casing 1. Said spindle rests against the lower ends of said slots as seen in Fig. 2. It is locked in said position by the casing 2 when the latter is closed, said casing having in one side wall 70 a slot 14 arranged on an arc drawing through the hinge 3 as a center and having in the other side wall an arc-shaped recess 15 pressed out of the metal and performing a function similar to that of the slot 14. As 75 will be apparent from Fig. 2, the spindle 7 is firmly locked against movement in any direction when the casing is closed. When the cover is thrown open, the spool with its spindle may be readily lifted out of the 80 diagonal slot and replaced with equal ease.

The pawl and ratchet 9 and 10, although arranged on the outer side wall of the casing proper 1, are, nevertheless, inclosed within the pressed-out channel 16 in the side wall of 85 the cover.

A bunch or package 17 of sheets of paper is arranged within the casing as shown in Fig. 2, that is, it is bent or hung over the roller 5 with the usual securing wire 18 at 90 one end thereof hooked onto a suitable catch 19, the latter being preferably an offset projection on a pivoted shield 20 having a pair of oppositely extending projections or lugs 21 received within suitable openings in the 95 side wall of the casing proper and constituting pivotal supports for said shield.

The opposite end of the package of paper 17 has a beveled appearance, that is, the sheets nearest to the roll 5 are bent through 100 an arc of the smallest radius and hence hang down lower than the outer sheets, which are bent through an arc of larger radius. The lower ends of said sheets rest against a suitable guide-plate or delivery-plate 22 which 105 may be mounted within the casing in any suitable manner, and which extends forward and downward. In the construction disclosed, it is secured at one end by hooks 23 struck up from the metal of the casing. It 110

is secured at the other end by lugs 24 which are embraced by struck-up ears 25 in the side wall of the main casing. It is also locked against forward movement by arms 26 5 secured thereto which engage notches or recesses 27 in the side walls of said casing. Said guide plate extends down to an opening 28 near the lower front corner of the casing, said opening being one through 10 which a single sheet at a time is adapted to project, whereby the successive sheets may be drawn downwardly by hand and removed from the casing. The shield 20 also projects into said opening and preferably slightly 15 through it, as shown in Fig. 2. In order to adjust the device for operation after a package of paper has been inserted, the knob 8 is turned slightly whereby the friction between the bands 6 and the inner sheet of 20 paper causes the latter to be advanced by the roller, thereby tearing it loose from the securing wire 18 and causing the lower end thereof to project a slight distance through the opening 28 beyond the end of the shield 25 20. In this position said sheet may be readily grasped by hand and withdrawn from the casing. Such withdrawal will serve to rotate the roller 5 whereby the next adjacent sheet is torn loose and caused 30 to project through said opening, whereby it may be withdrawn subsequently in the same manner as the first sheet. It will be seen that the roller 5 is rotated by the sheet which is being withdrawn by hand, only so 35 long as the inner end of said sheet remains in contact with said roller. The next adjacent sheet is advanced, therefore, only during the brief interval that the friction band 6 is rotating in contact therewith. 40 This interval corresponds to the rotation of the roller through an angle of perhaps 180° or less as the inner end of any given sheet is being withdrawn from over the roller. 45 In order to insure the holding of the package of paper against the roller and thereby increase somewhat the friction between the roller and the adjacent sheet, I provide a suitable arm 29 which is fixed to a supporting rod 30, the latter being mounted at opposite ends in the side walls of the cover 2. Said rod may have affixed thereto at one end and outside of the cover a suitable pointer or indicator 31 which will move 50 gradually with the arm 29 through a small arc as the successive sheets are withdrawn, due to the decreasing thickness of the remaining package of paper. A glance at said pointer will indicate in a general way the 55 amount of paper remaining, whereby a new package may be inserted when the receptacle becomes empty. The arm 29 is bent downwardly at its forward end as shown, whereby when the cover is opened said arm projects nearly at right angles from said cover 60 65 70 75 80 85 90 95 100 105 110 115 120 125 130

and accordingly when the cover is closed the other end of said arm, which is curved upwardly, rides freely over the curved package of paper without having to be manipulated and without catching on the same. 70

The shield 20 has the effect of reducing the effective size of the opening 28 to a narrow slit, just sufficient to permit the exit of a single sheet of paper. Said shield normally tends to close said opening, but, as there is usually at least a single sheet of paper projecting therethrough, said opening is never entirely closed, except when there is no paper whatever in the receptacle. 75

It will be seen that the wire 18 is connected with the catch 19 at a point offset somewhat with respect to the shield 20. Accordingly whenever any paper is being drawn from the receptacle and the roller 5 is rotating, there is a slight tension or pull on said wire 18 which tends to rock the shield 20 outwardly, thereby releasing the friction on the paper as it is being drawn through the opening. As the paper may be of thin tissue, which tears very readily, this automatic release of the pressure thereon insures the removal of the entire sheet without mutilating it. 85 90

Through ignorance or maliciousness it has been the practice in prior instances, where a paper feeding receptacle of this character has failed to operate so as to leave a protruding sheet, to insert a knife or some other object and endeavor to drag the next sheet out, thereby mutilating the paper and often disarranging the device so as to obstruct the further satisfactory operation in the intended manner. The main function of the shield 20 in the present instance is to prevent or render difficult such tampering with the device, and the knob 8 being plainly visible, the user is more apt to try the experiment of turning the knob than to attempt other expedients when there is no protruding sheet of paper waiting to be grasped. The knob cannot be turned the wrong way by virtue of the pawl and ratchet mechanism, and the turning thereof in the only direction permitted will advance a sheet at any stage of the operation. 100 105 110 115

From the above description it will be seen that we have provided a device wherein the normal operation, namely the partial advance of any one sheet by the withdrawal of the preceding sheet, is positive and reliable. We have provided further, means whereby if for any reason a sheet should not be left protruding from the receptacle the obvious thing to do is to turn the handle 8, which will advance the sheet in the desired manner, after which the normal operation will be continued. We have provided further a device in which unauthorized tampering with the interior mechanism is prevented, all the parts being inclosed and protected 120 125 130

and locked by a single lock. The insertion of knives or other objects into the feed slot is substantially prevented. The roller is readily removable and yet is locked in position whenever the casing is closed and the design of the parts is such that the device lends itself to economical manufacture and quick assembly.

What we claim is:

- 10 1. In a device of the class described, in combination, means for supporting a package of paper so as to permit one sheet thereof to project from an opening therein, the withdrawal of one sheet serving to cause the next sheet to protrude therefrom, and a pivoted shield adjacent said opening and adapted to restrict said opening to a size necessary to permit the issuance of the desired sheet, said shield coöperating with said paper in
- 15 20 such a manner as to tend to relieve its pressure on the issuing sheet as it is being drawn from the receptacle.

- 20 2. In combination, a casing and cover hinged thereto at its lower end and having an opening therein, a diagonally arranged guide plate within said casing, said guide plate extending to said opening, a friction roller, a spindle therefor, said spindle pro-

jecting through slots in the side walls of said casing, an arc-shaped slot in said cover 30 curved about the pivotal connection as a center, said slot being adapted to receive one projecting end of said spindle, a handle on said projecting end, a ratchet on the opposite end of said spindle, said ratchet being received within a pressed out channel in the cover, whereby said ratchet and its coöoperating pawl are inclosed thereby, a shield pivotally supported within said casing and extending to said opening, an offset 40 projection on said shield whereby one end of a package of paper bent around said roller may be secured to said projection and thereby tend to swing said shield when tension is applied to said paper, and a friction arm 45 suitably mounted in said cover and adapted to press said paper against said roller.

In witness whereof, we hereunto subscribe our names this tenth day of March, A. D., 1913.
